UNITED STATES PATENT OFFICE

119,595

DESIGN FOR A BATTERY BOX

Raymond Le Clercq, Los Angeles, Calif.

Application August 7, 1939, Serial No. 86,494

Term of patent 14 years

To all whom it may concern:

Be it known that I, Raymond Le Clercq, a citizen of the United States, residing at Los Angeles, in the county of Los Angeles and State of California, have invented a new, original, and ornamental Design for a Battery Box, of which the following is a specification, reference being had to the accompanying drawing, forming a part thereof.

Figure 1 is a front elevational view;

Figure 2 is an end elevational view; and Figure 3 is a rear elevational view, of a battery box showing my new design.

The top view (not shown) consists of the conventional oblong box divided by partitions into three compartments.

I claim:

The ornamental design for a battery box, as shown and described.

RAYMOND LE CLERCQ.
